UNITED STATES PATENT OFFICE.

LEWIS L. SCOTT, OF ST. LOUIS, MISSOURI.

THROTTLE CONTROL FOR STEAM AUTOMOBILES.

Application filed August 5, 1921. Serial No. 490,064.

To all whom it may concern:

Be it known that I, LEWIS L. SCOTT, a citizen of the United States, residing in the city of St. Louis and State of Missouri, have invented new and useful Improvements in Throttle Controls for Steam Automobiles, of which the following is a specification.

This invention relates to a novel apparatus for controlling the flow of steam from the boiler to the engine of a steam automobile. The invention is designed more particularly for use in steam automobiles, although not limited to such application, and the leading characteristics thereof are, that by means of the apparatus herein described I am able to operate the steam throttle valve, which opens against high steam pressure with very little power.

The object of this invention is to provide a simple means for balancing the steam throttle valve so that the same can be operated by a foot lever as well as a hand lever.

The steam pressure used on steam automobiles is usually 600 lbs. It is desirable to arrange the throttle valve so that it opens against the steam pressure, so that said steam pressure will tend to keep the throttle valve closed. The usual method of opening the throttle valve is with a hand lever located on the steering wheel column. It is very difficult to properly control the flow of steam with a hand throttle that is unbalanced, it is next to impossible to operate an unbalanced throttle with a foot lever. It is very desirable to have the throttle arranged so that it can be operated with a foot lever as well as a hand lever, so that both hands may be used to manage the steering wheel.

The invention is illustrated in the accompanying drawings in which: Figure 1 is a plan view of the rear end of a steam automobile, the front part of frame being broken away. Figure 2 is a sectional view of the throttle valve and parts controlling same. Figure 3 is a side view of Figure 2, same parts being broken away.

Referring now to the drawing, the numeral 1 indicates the body of the throttle valve, 2 is the throttle valve which has its seat at 3 in the body 1. Steam enters the casting 1 through the pipe 4 (from the boiler which is not shown) and when the throttle valve 2 is open, passes through the

pipe 5 to the engine 6 which is mounted on the rear axle as shown in my United States Patent 1,358,117 of November 9, 1920. 7 indicates the frame and 8 indicates the rear wheels of an automobile.

The throttle valve 2 is provided with a stem 9 which projects out through the casting 1. A stuffing box 10 prevents leakage of steam past the stem 9. The stem 9 carries a lug 11. A connecting rod 12 is attached to lug 11 by the pin 13, the other end of the connecting rod 12 is mounted on the crank pin 14 of the crank arm 15, said crank arm 15 is secured to the throttle rod 16 so that if the throttle rod 16 is oscillated the throttle valve 2 will be either opened or closed. A bearing 17 supports the rod 16 at its lower end, and the bearing 18 supports the rod at its upper end. 19 indicates the steering column of an automobile. The bearing 18 is secured to the steering column. 20 indicates the hand lever which is secured to the end of the rod 16. Any suitable means may be provided for latching said hand lever when the throttle valve 2 is in a closed position. The part 21 is secured to the rod 16 and bears against a spring 22, the spring 22 being adjustable by the screw 23. The spring 22 is adjusted so that it will just balance the working steam pressure. That is to say, the part 21 acts as a lever, under the power of spring 22, and tends to turn the rod 16 in a direction to force the stem 9 and valve 2 inward against the pressure of the steam on the valve holding it to its seat. When the valve 2 is opened, the power of spring 29 is exerted, on release of the hand or foot throttle, to close the valve, should the adjustment of balance by spring 22 be such as to permit the valve to be balanced by steam pressure in an open position in the casing 1. The valve 2 is practically balanced by the steam, after said valve is opened. 24 indicates a bevel gear which is secured to the rod 16. A bevel gear 25 meshes with the gear 24 and is secured to the shaft 26 which shaft is carried by the bearing supports 27. A lever 28 is secured to the shaft 26, said lever being adapted to be operated by the foot.

A spring 29 is attached to the arm 30 of the lever 28 for the purpose of returning levers 20 and 28 to normal position when they are released.

It is assumed that the spring 22 is ad-

justed so as to just balance the steam pressure so that very little effort will be required to open the throttle valve, which can be operated either by hand lever 20 or foot lever 28. After the throttle valve 2 has been opened, say by operating lever 28, and it is desired to stop the engine 6, all that is necessary is to release the lever 28 and the spring 29 will close said valve 2 as will 10 be plainly seen. It will be observed that the valve is balanced by means located exteriorly of the casing of the valve, and hence such means are not exposed to moisture or heat from the steam, either of 15 which would have a deleterious action on the balancing means. That is to say, variations in temperature would result in variations in the tension of the spring 22, in the specific embodiment of my invention shown, 20 and moisture would, of course, exert its ordinary corroding effect.

I claim:

1. A valve for controlling the flow of steam to a steam engine, comprising a valve 25 casing, a valve therein subject to the pressure of the steam, a manually-operated device associated with said valve for opening and closing the same, and means located exteriorly of said casing and associated 30 with said opening and closing device for balancing said valve against the steam pressure.
2. A valve for controlling the flow of steam to a steam engine, comprising a valve 35 casing, a valve therein seated by the pressure of the steam, and having a stem projecting beyond the casing, a manually-operated device for operating said stem to open and close said valve, and means asso-

ciated with said opening and closing device and located exteriorly of said casing for balancing said valve against the steam pressure.

3. A valve for controlling the flow of steam to a steam engine, comprising a valve 45 casing, a valve therein subject to the pressure of the steam, a manually-operated device associated with said valve for opening and closing the same, and a spring as- 50 sociated with said opening and closing device and located exteriorly of said casing for balancing said valve against the steam pressure.

4. A valve for controlling the flow of steam to a steam engine, comprising a valve 55 casing, a valve therein seated by the pressure of the steam, a manually-operated device associated with said valve for opening and closing the same, and a short scale 60 spring associated with said opening and closing device and located exteriorly of said casing for balancing said valve against the steam pressure.

5. A valve for controlling the flow of steam to a steam engine, comprising a valve 65 casing, a valve therein, a manually-operated device associated with said valve for opening and closing the same, a spring as- 70 sociated with said opening and closing device and located exteriorly of said casing for balancing said valve, said spring tend- 75 ing to open said valve, and the steam pres- sure within said casing tending to keep the valve closed.

In testimony whereof, I have hereunto set my hand.

LEWIS L. SCOTT.
